ABSTRACT

This invention concerns an energy absorbing liner structure at the inside of a sodium-steam generator wall which consists of two concentric thin-walled cylinders. Thin-walled tubes filled with tight compacted steel wool are fitted in the space between the two concentric cylinders. This energy absorbing structure will prevent damage to the vessel wall resulting from the effects of a sodium-water reaction.

ENERGY ABSORBING STRUCTURE IN A STEAM GENERATOR

BACKGROUND OF THE INVENTION

The present invention consists of improvements in liquid sodium heated steam generators and/or superheaters by providing a protection against a possible sodium-water reaction. Tube failures have occurred in the past and will occur in the future in conventional steam generators. The normal procedure to solve this problem was to shut down the generator and to plug or replace the damaged tube. If a tube fails in a sodium-steam generator, a violent sodium-water reaction will take place, which may cause major damage to the internal structure and the vessel shell. The probability of tube failure over the life span of the generator is appreciable, and it is therefore believed that the vessel shell should be protected from the effects of the pressure wave caused by a violent sodium-water reaction. The possible effects on the shell are excessive permanent straining of the wall, excessive elastic straining of the wall, or rupture.

SUMMARY OF THE INVENTION

The object of the present invention is to prevent damage to the steam generator vessel wall which may result from tube failure and a consequent sodium-water reaction. To prevent such damage, an energy absorbing liner-structure shall be utilized inside the vessel boundary which encloses all internal structures. The energy absorbing structure has the advantage of being easily replaceable, lightweight, sodium resistant, temperature resistant, easily fabricated, and shall not interfere with the overall operating purpose of the generator.

BRIEF DESCRIPTION OF THE DRAWINGS

FIG. 1 is a cross section of a steam generator embodying the present invention as a liner structure along the inner periphery of the steam generator.

FIG. 2 shows an expanded portion of said liner structure showing a cross section of the thin-walled tubes with compacted steel wool used as fillers in the absorbing liner.

FIG. 3 shows an alternate configuration in which the space between the concentric cylinders of the liner structure are fitted with corrugated sheet metal, with compacted steel wool again being used as fillers.

DESCRIPTION OF THE PREFERRED EMBODIMENT

In FIG. 1, a cross section of a steam generator is shown, with the energy-absorbing liner (1) of the present invention disposed along the inner periphery of the steam generator (2). The steam generator has an outside diameter of approximately 40 inches and the liner

55

structure has an outside diameter of approximately 36 inches. The energy-absorbing liner consists of two concentric thin-walled cylinders (3) of 304 stainless steel, three-eighths inches thick with approximately one inch

5 between cylinder walls. The space between said concentric cylinders is filled with a plurality of tubes (4) of 304 stainless steel, five-eighths inches in diameter and 0.072 inches thick, each of said tubes being packed with compacted steel wool to a density of approximately 0.07 lbs/in.³ (FIG. 2).

As an alternate configuration, the space between the thin-walled cylinders may be fitted with corrugated sheet metal (5), of approximately one-eighth inch thickness and with corrugation of approximately one-half inch pitch. The sheet metal is folded between said cylinders as shown in FIG. 3, with the spaces in between again being packed with compacted steel wool to generally the same density as that packed in the tubes.

It is to be understood that the embodiment given above is presented by example only, and not in a limiting sense. The dimensions given above and the density of steel wool are not critical, the scope of the present invention being determined by the claims.

What is claimed is:

1. Apparatus for absorbing energy comprising:

a. two concentric thin-walled cylinders,
b. a plurality of thin-walled tubes disposed in the zone between said cylinders in an abutting relationship with each other and with said cylinders, said tubes extending along the entire length of said cylinders and being tightly filled with compacted steel wool.

35 2. The apparatus of claim 1 wherein the outer cylinder has an outside diameter in the range of from 34 to 40 inches, and an inside diameter in the range of from 33½ to 39½ inches, and the inner cylinder has an outside diameter in the range of from 32½ to 38½ inches and an inside diameter in the range of from 32 to 38 inches.

3. Apparatus for absorbing energy comprising:
two concentric thin-walled cylinders, said cylinders being fitted with corrugated sheet metal disposed between said cylinders and in an abutting relationship thereto, and with the zone between said cylinders being filled with tightly compacted steel wool.

40 4. The apparatus of claim 3 wherein the outer cylinder has an outside diameter in the range of from 34 to 40 inches, and an inside diameter in the range of from 33½ to 39½ inches, and the inner cylinder has an outside diameter in the range of from 32½ to 38½ inches and an inside diameter in the range of from 32 to 38 inches.
